HENRY ASHFIELD, OF CHICAGO, ILLINOIS.

Letters Patent No. 97,472, dated December 7, 1869.

SAFETY-VALVE.

The Schedule referred to in these Letters Patent and making part of the same.

To whom it may concern:

Be it known that I, HENRY ASHFIELD, of Chicago, in the county of Cook, and State of Illinois, have invented a new and useful Improvement in Safety-Valves; and I do declare that the following is a true and accurate description thereof, reference being had to the accompanying drawings, and to the letters of reference marked thereon, and being a part of this specification, in which—

Figure 1 is a vertical section of the device;

Figure 2 is a plan view of the top of the interior of the valve-cover; and

Figure 3 is a plan view of the bottom of the valve-seat plate.

Like letters of like kind designate like parts in each figure.

This invention belongs to the class of safety valves for the escape of steam from boilers, intended to be guarded against any loading, fastening down, or tampering on the part of the engineer; and

It consists in the novel construction of the valve proper, and of its stem.

It also consists in the peculiar form of the valve itself, and, in combination with it, of a sleeve to cover the spiral spring, which is operated by the valve, so that the escaping steam does not come in contact with it; also, in the peculiar arrangement of the devices for regulating the pressing force of said spring; also, in the means by which the valve-stem is supported above and below the valve; also, in the peculiar form of the top of the valve-stem; also, in the false perforated roof, cast into and with the top of the cover; also, in the braces cast into and with the bottom of the valve-seat.

A represents the valve-seat plate, and is a circular disk of suitable diameter and thickness, with two or more braces B cast with it and upon the centre of its bottom.

The braces B arch downward from said bottom, leaving a space of the shape of a segment of a circle between them and the bottom of the valve-seat.

These braces are perforated at the centre with an opening, C, for the reception of the valve-stem.

The valve-seat plate A is provided, at its centre, with a proper valve-seat, D, tunnel-shaped, largest at the top.

The cover E rests upon and is firmly secured to the plate A.

It is a hollow dome-shaped casting, having a false perforated roof, F, cast into and with it. This false roof has a solid centre, and is connected by radial arms with the inside of the cover E, and is arched across it near its top.

This cover has also an opening, G, near its top, for the admission of a lever and ears, H, between which the lever is pivoted.

I is the valve, which is of the general form of the frustum of one right cone placed above another, the larger uppermost, with the smaller ends of each downward, which form is used for the purpose of keeping the upper part of said valve as cool as possible, and thus protecting the valve-spring resting upon it from heat. This valve fits at its bottom with perfect accuracy to the valve-seat D.

A steel spiral spring, K, rests upon the top of the valve, and is regulated by a nut, L, which presses upon its top.

The nut L works upon a threaded sleeve, M, which extends downward a little way in the interior of the spring K, the upper part of which embraces a washer, N, which protects the threads of the sleeve from injury from the spring.

Above the nut L and screwed upon the sleeve M, is the nut O, which is circular, and of the same size as the top of the valve I.

A frame, P, stands upon and is secured to the valve-seat plate A. The top of the sleeve M passes through, and is firmly screwed into the top of this frame.

The valve-stem Q passes through this frame, downward through the sleeve M, the interior of the spring K, the centre of the valve I, and the opening C in the brace B.

The stem plays loosely at all points except in the valve, in which it is tightly screwed, and at the top terminates in a hammer-shaped head, R, fitting closely to the top of the sleeve M, when the valve I is closed, and provided with a slot for the reception of the end of the lever S, which is pivoted on the ears H, and works in the opening G in the cover.

A suitable opening, T, in the top of the cover, permits the escape of steam.

The spring K is covered with a cylindrical jacket, V, made of suitable sheet-metal, which is firmly secured to the sides of the top of the valve I, and extends upward, covering said spring K and the nut L, and just encloses the bottom of the sides of the nut O, fitting closely to the same.

In the operation of this device the pressure of steam required to move the spring, and thus open the valve, may be ascertained before securing the frame P in place, by weight upon the lower end of the valve-stem; or by a dynamometer attached to the head of the valve-stem. As the force required to operate the spring and raise the valve increases as the nut L is screwed down toward the valve, and the spring is thus shortened, a scale or series of marks may be employed to show the force of pressure required to operate the valve at various positions of the nut L.

When the apparatus is to be used, it is intended that the valve-seat plate shall be the head of the dome, and be firmly secured to it.

It will be seen that by the peculiar construction of

this safety-valve, it will be impossible for the engineer, when it is in use, to get at any part of it for the purpose of loading or fastening it down; that the spring, being covered with the jacket V, which moves with the valve, is protected from contact with the steam, and thus it will be uniform at all times in exerting the same downward pressure, by which greater accuracy will be attained than is possible where the spring is uncovered; that the valve, being supported above and below, in the manner described, cannot trip or get out of order.

I do not claim broadly the invention of a jacket to cover and protect the valve-spring from escaping steam, neither do I claim the method by which said jacket is connected with said valve in the invention of H. W. Hewet, patented August 18, 1868; but

What I do claim as my invention, and desire to secure by Letters Patent, is—

1. The valve I, constructed as shown and described, and operating as and for the purpose set forth.
2. In combination with the valve I, and rigidly attached to its outer upper part, the jacket V, con-

structed as shown and described, and operating as and for the purpose set forth.

3. In connection with the valve I, and attached to it, the valve-stem Q, playing loosely in the sleeve M, supported by the brace B, and provided with the head R, all constructed as shown and described, and operating as and for the purpose set forth.

4. In combination with the sleeve M, the washer N, when constructed as shown and described, and operating as and for the purpose set forth.

5. The combination of the sleeve M, the nut L, the washer N, and the spiral spring K, when constructed as shown and described, and operating as and for the purpose set forth.

6. The braces B, cast into and with the valve-seat plate, as shown and described, and for the purpose set forth.

HENRY ASHFIELD.
